Benjamin Gordon Inventor

By his Attorney
George F. Mattick

UNITED STATES PATENT OFFICE.

BENJAMIN GORDON, OF NEW YORK, N. Y.

TAG.

1,353,952.

Specification of Letters Patent. Patented Sept. 28, 1920.

Application filed December 26, 1919. Serial No. 347,572.

To all whom it may concern:

Be it known that I, BENJAMIN GORDON, of New York city, New York, have invented certain Improvements in Tags, of which the following description, in connection with the accompanying drawings, is a specification, like reference characters on the drawings designating like parts.

This invention relates to tags and is of particular utility when embodied in the construction of non-detachable price tags for garments, although I contemplate the utilization of my improvements in any field for which they are adapted by their nature.

An important object of my invention is to provide a tag of this type having a metallic capsule to support a ticket bearing the price mark or other legend, and chambered to serve as a lock casing in coöperation with a flexible metallic attaching member, preferably formed integrally of spring wire with its ends entering apertures in the periphery of the capsule, and its medial portion constituting a loop to pass through a button hole or other attaching portion of the garment to which the device is to be secured nondetachably, its detachment being only possible upon severance of the flexible member, which indicates that it has been tampered with and can no longer be relied upon as an accurate price indication.

A distinctive and important feature of my invention is the formation of this flexible metallic member in such fashion that one end is so bent as to oppose a loop or shoulder to the withdrawal of that portion of the wire included permanently within the capsule to secure the flexible member therewith, this portion of the wire being continued around within the capsule to surround a capsule-aperture arranged to receive the normally free locking end of the flexible member, with an eye formed in such a manner that the locking end of the flexible member will be engaged upon its entrance through the capsule aperture and the eye, and will be directed into locking engagement therewith.

My improved tag comprises a minimum number of parts, resulting in economy of material, certainty and simplicity of attachment, durability of construction and adaptability to a wide range of uses, with small opportunity for getting out of order, or its injury by intentional tampering or careless handling.

The various features of my invention will be illustrated and described fully in the accompanying drawings and specification and pointed out in the claim.

60

In the drawings,

Figure 1, is a view in front elevation of a non-detachable price tag in the construction of which my improvements have been embodied, and

65

Fig. 2, is a detail view of the attaching member, shown separately.

In the embodiment of my invention selected for illustration and description to enable ready and complete understanding of my improvements, the part designated by the reference numeral 1, is the attaching member of a price tag for a garment 2, of which latter a portion only is shown, as it forms no part of my invention and may be of any suitable character, being illustrated with a button hole 3 through which is passed the loop of the attaching member 1, the ends 4 and 5 of the same being locked permanently within a casing or capsule 6 when in position for use, so that the tag is non-detachable from the garment and affords a reliable support for such a price indication as that shown as marked upon the price ticket 7, the latter being of any suitable character.

85

The attaching member 1 and lock casing 6 may be of any material and structure suitable to carry my invention into effect, and as one suitable material for the attaching member 1, I may employ wire, preferably using a single piece with integrally formed securing portions 8—9 and 10 to be engaged with the lock casing 6 and with each other when in operative position.

95

So also I may form the lock casing 6 as a metallic capsule comprising preferably a body portion chambered or recessed at 11 to receive a coiled portion 12 of the attaching member 1 which as shown in Fig. 1 lies in an aperture 12^a formed in the periphery of the capsule, and is held therein by a shoulder or bend 8, one end 5 of the attaching member extending freely outside the wall of the capsule to form the attaching loop, which has near its free end a locking bend 9 to be inserted within another peripheral aperture 13 of the capsule and to be there caught and held permanently against displacement.

105

As shown in Fig. 1, an important feature of my invention consists in providing the at-

110

taching member 1 with an eye 10 near the end of the portion coiled within the capsule 6, and so locating the eye 10 that it is normally in position opposite the aperture 13 to receive the locking bend 9 of the attaching member, and the material of the same being somewhat resilient the coil 12 tends to move the loop 10 into engagement with the bend 9 and insure locking action of the bend and assisting to prevent tampering with the interior of the capsule.

The attaching member 1 may have its bend 8-9 and 10 formed before assembly with the capsule 6 and the latter will preferably be given the dished shape illustrated in Fig. 1 before receiving the attaching member, a shoulder 14 being formed upon the capsule to aid in locating properly the coiled portion 12 and to form a seat for a closure member 15 which serves as a backing for the price ticket 7, the rim 16 being swaged over to retain the capsule parts in assembled relation.

The device may thus be formed simply of four members, viz., the capsule proper 6, the flexible attaching member 1, the closure disk 15 and the price ticket 7 and as the bends 8, 9 and 10 can be formed in the integral attaching wire 1 while still separate, it is only necessary to pass the free end 9 through the aperture 12^a, then coil the part 12 with the loop 10 in position opposite the aperture 13, insert the disk 15 and ticket 7 in place and swage over the rim 15 to complete the device, which is then ready for attachment to the garment 2 by thrusting the free end 4 through the button

hole 3 and into the aperture 13, by which operation the locking of the latter is effected automatically with the bend 9 engaged with the loop 10 permanently.

Having illustrated and described my invention thus fully, and suitable means for carrying the same into effect, it is to be understood that I do not limit myself to the specific material and construction selected for illustration and description, nor in general do I limit myself otherwise than as set forth in the claim, read in connection with this specification.

What I claim as new and desire to secure by Letters Patent of the United States of America, is:—

A non-detachable tag comprising a lock casing consisting of a metallic capsule having a plurality of peripheral apertures, a metallic closure secured thereto, and a flexible metallic attaching member coiled between said capsule and closure with a retaining portion provided with a detent eye opposite one of said apertures and an attaching portion extending through another of said apertures, the free end of said attaching member having a locking bend to pass into said detent eye through the adjacent aperture and to be engaged in locking relation therewith.

Signed at New York, in the county of New York, and State of New York, this 15th day of December, 1919.

BENJAMIN GORDON.
